DESK CADDY

Ira Saltz, Greenlawn, N.Y., assignor to Oxford Pendaflex
Corporation, Garden City, N.Y.

Filed Sept. 28, 1972, Ser. No. 295,984

Term of patent 14 years

Int. Cl. 19—02

U.S. Cl. D74—5 A

FIG. 1

FIG. 2

FIG. 3

FIG. 5

FIG. 6

FIG. 7

FIG. 8

FIG. 9

FIG. 10

FIG. 11

FIG. 12

FIG. 13

FIG. 14

FIG. 1 is a perspective view of a desk caddy in a closed condition, showing my new design in transparent form;

FIG. 2 is a perspective view thereof in an open condition;

FIG. 3 is a top plan view;

FIG. 4 is a left side elevational view, the side opposite thereto being similar;

FIG. 5 is a rear elevational view;

FIG. 6 is a bottom plan view;

FIG. 7 is a front elevational view;

FIG. 8 is a perspective view of the desk caddy in a closed condition, shown in opaque form;

FIG. 9 is a perspective view thereof in an open condition;

FIG. 10 is a top plan view;

FIG. 11 is a left side elevational view, the side opposite thereto being similar;

FIG. 12 is a rear elevational view;

FIG. 13 is a bottom plan view; and

FIG. 14 is a front elevational view.

I claim:

The ornamental design for a desk caddy, as shown and described.
